(57) **CLAIM**

The ornamental design for a reclining lounge chair, as shown and described.

DESCRIPTION

FIG. 1 is a front perspective view of a first embodiment of a reclining lounge chair with the backrest in a raised position showing my new design;

FIG. 2 is a front perspective view of a second embodiment with the backrest in a lowered position;

FIG. 3 is a slightly enlarged front elevational view;

FIG. 4 is a slightly enlarged rear elevational view of FIG. 2;

FIG. 5 is a slightly enlarged top plan view of FIG. 2;

FIG. 6 is a slightly enlarged bottom plan view of FIG. 2;

FIG. 7 is a slightly enlarged right side view of FIG. 2; and,

FIG. 8 is a front perspective view similar to FIG. 1 showing a pair of armrests.
